UNITED STATES PATENT OFFICE.

FRANK A. WEEKS, OF PLAINFIELD, NEW JERSEY.

INKSTAND.

Application filed February 20, 1924. Serial No. 694,033.

To all whom it may concern:

Be it known that I, FRANK A. WEEKS, a citizen of the United States, and a resident of Plainfield, in the county of Union and State of New Jersey, have invented certain new and useful Improvements in Inkstands, of which the following is a specification.

The inkstand of this invention comprises a glass base containing an inkwell and having a recess surrounding the upper edge of the well and sunken into the solid top surface of the base, and a novel cover for the well comprising a base member adapted to said recess, tilttable closure-sections hung from said base member and an upper outer ring member which is hollow and encompasses a central circular standard or elevation forming a part of said base member, said ring member having an open center exposing said closure sections.

One purpose of the invention is to provide an inkstand of the class involved herein, in which the cover portion is elevated above the well and spaced outwardly from the edges thereof and of such construction that the cementing of the cover to the base by dried ink is avoided.

Another purpose of the invention is to provide a durable and efficient cover construction, and a further purpose is to secure a superior action in the tilttable closure sections by providing a novel formation of the trunnions connected with said sections. A further object of the invention is to so construct the cover that the tilttable closure sections are kept out of contact with the ink in the well, and at the same time permit of the use of an adequate supply of ink in the well.

The invention will be fully understood from the detailed description hereinafter presented, reference being had to the accompanying drawings, in which:

Fig. 1 is a plan view of an inkstand embodying my invention;

Fig. 2 is a central vertical longitudinal section of the same, taken on the dotted line 2-2 of Fig. 1;

Fig. 3 is a like view of the same, showing the position given to the tilttable closure sections by the act of dipping a pen into the ink-well;

Fig. 4 is a vertical transverse section through the inkstand, taken on the dotted line 4-4 of Fig. 1;

Fig. 5 is a top view of the base member of

the main ink-well cover, the same being shown without the tilttable closure sections and superposed finishing ring member.

Fig. 6 is a detached bottom view of the upper finishing ring member, and

Fig. 7 is a perspective view of the two tilttable closure sections detached from the other parts of the inkstand.

In the drawings 10 designates the glass base or body of the inkstand, which base contains an ink-well 11 to receive ink 12 and has a main flat top surface 13 and a rectangular recess 14 extending around the upper end of the well 11 and defined by a flat bottom 15 and vertical walls 16, the rear one of which is rearwardly concaved in the middle portion 17 thereof. The base 10 may be formed with a forward pen-rack 18.

The cover for the ink-well comprises a base member 19, depending tilttable closure sections 20 supported from said base member and a superposed finishing ring member 21, which is open at its center and thereat encompasses, while being free of, the upper edges of the closure sections 20.

The base member 19 has a rectangular lower portion adapted to substantially fill the recess 14 in the base 10, said lower portion comprising a vertical edge flange 22 snugly, though freely, engaging the vertical walls 16 of said recess and resting upon the aforesaid flat bottom 15, and a flat table section 23 from whose edges said flange 22 depends and which is disposed somewhat above the plane of the top surface 13 of the base 10. At its rear end the table section 19 is rearwardly curved, at 24 (Fig. 5), to fill the curvature 17 in the rear wall 16 of the recess 14. The flange 22 serves to elevate the ink-well cover parts over the well so that said parts remain clear of the ink in the well, and also as means in cooperation with the recess 14, for positioning the cover on the base 10. Upon the table section 23 of the base member 19 is formed a circular elevation 25 of substantial height positioned centrally over the ink-well, and this elevation 25 has a central vertical com-

modious opening 26 within which the closure sections 20 are suspended and have their swinging movements toward and from each other. Within the upper end of the opening 26 are formed two opposite semi-circular recesses 27, 28 (Fig. 5), adjacent to whose facing ends are formed transverse recesses 29 which serve as bearings for the trunnions

30 on the closure sections 20. The walls of the opening 26 below the recesses 27, 28 flare outwardly and downwardly to afford adequate space within which the closure sections 20 may have their movements away from and toward each other.

The closure sections 20 when together form a circular downwardly tapering cup outline and said sections are of equal size 10 and each has along the outer edges of its upper end an outwardly set semicircular rib 31, the ribs 31 being adapted to enter and seat on the bottom wall of the recesses 27, 28, as shown in Fig. 2. The closure sections 20 at their upper inner facing edges are formed integrally with the aforesaid 15 trunnions 30, which come together in the bearing recesses 29 and have vertical flat lower matching surfaces 32 and upper outwardly diverging surfaces 33. The exterior surfaces of the trunnions 30 are rounded to match the concave surfaces at the lower ends of the recesses 29. When the closure sections 20 are in their normal closed position, as shown in Fig. 2, their facing edges are closed together, the flat surfaces 32 of the trunnions 30 are matched against each other and the ribs 31 are seated in the recesses 27, 28, and said sections automatically 20 remain in this closed condition until disturbed by the introduction of a pen between them, as shown in Fig. 3. The introduction of the pen causes the closure sections 20 to open outwardly from each other 25 at their lower portions and the trunnions on the respective sections to turn in opposite directions in the bearing recesses 29, the flat surfaces 32 on the trunnions opening outwardly and the fulcrum points of 30 the trunnions being on the angle lines between the surfaces 32, 33 of the trunnions, as shown in Fig. 3; at this time the diverging surfaces 33 close toward each other and their presence, without unduly weakening 35 the trunnions, lowers the bearing points of the trunnions against each other to substantially a transverse center line through the trunnions, whereby a superior turning action of the trunnions in their bearings 40 and a superior movement of the sections 20 are secured.

After the closure sections 20 have been positioned on the base member 19, the ring member 21 is applied upon said base member and cemented thereto so that all the parts of the cover become permanently assembled and may be handled as a unit. The ring member 21 has an open center surrounding the opening 26 in the base member 19, and the central portion of the ring member 21 around its open center curves downwardly and inwardly and has a flat annular lower edge 34 which seats upon the inner annular portion of the flat top of the elevation 25 and closes the upper ends of the

bearing recesses 29, thus confining the trunnions 30 in said recesses and thereby maintaining the permanent connection of the closure sections 20 with the other members of the cover. The ring member 21 is hollow and closely encompasses the elevation 25 and the lower edge of the outer annular wall of said member 21 is flat and bears upon and is cemented to the table section 23 of the base member 19, the cementing of the ring member 21 to the base member serving to secure all the parts of the cover together as a unit. 70

The purpose of the curvature 17 in the rear wall 16 and that of the curvature 24 on the base member 19 entering said curvature 17, is to compel the correct application of the cover to the base 10 so that the joint between the closure sections 20 shall be transverse of the inkstand. 80

The manner of employing the inkstand will be understood without detailed explanation. The cover is lifted off from the base, when ink is to be supplied to the well and is thereafter restored to position in the recess 14 of the base. The recess 14 is an important feature of the inkstand, since it permits of the employment of a rectangular base member 19 supported wholly without the well 11 and spaced from the edge surfaces of the well, danger of the cover being cemented to the base 10 by dried ink being thereby avoided. It should be mentioned that the cover construction is such that the tilttable closure sections are held clear of the ink in the well and are so positioned that an adequate supply of ink in the well is permitted. 90

The construction as a whole is one of special efficiency and good appearance.

What I claim as my invention and desire to secure by Letters Patent, is:

1. An inkstand comprising a base having an inkwell therein and a recess surrounding the upper edges of said well and extending laterally therefrom, and a removable cover adapted to said recess and comprising a base-member having an elevated central portion containing a vertical opening and bearing-recesses at opposite sides of the upper portion of said opening, tilttable closure sections having side trunnions mounted in said bearing-recesses and suspended within said opening and an outer hollow ring-member encompassing said elevated portion and at the lower edge of its sides engaging said base member and at its upper portion being extended over and engaging the top of said elevated portion around the opening therein and closing the upper ends of said recesses. 110

2. An inkstand as claimed in claim 1, in which said base member has a depending edge flange to fit the side walls of said recess and engage the bottom of the recess outwardly from the well, a table portion and said elevated portion extending upwardly 120

125

130

therefrom, and in which the sides of said ring member seat on said table portion.

3. An inkstand as claimed in claim 1, in which said recess is rectangular and sunken 5 into the flat top of the glass base, and in which said base-member is rectangular and fits said recess and comprises a table-section and said elevated portion arising from the central part thereof, and in which said ring- 10 member is circular and has the lower edges of its sides seated on said table-section.

4. An inkstand as claimed in claim 1, in which the pairs of trunnions on said closure 15 sections have facing surfaces which are flat on their lower matching portions and divergent on their upper portions, whereby said sections on their opening and closing movements turn on the angle lines separat-

ing said flat and divergent portions of the trunnions.

5. An inkstand as claimed in claim 1, in which said recess is rectangular and sunken 20 into the flat top of the glass base, and in which said base-member is rectangular and has a depending edge flange to fit the side 25 walls of said recess and engage the bottom of the recess outwardly from the well, a table-section and said elevated portion arising from the central part thereof, and in which said ring-member is circular and has the 30 lower edges of its sides seated on said table-section.

Signed at New York city, in the county of New York and State of New York, this 15th day of February A. D. 1924.

FRANK A. WEEKS.
